UNITED STATES PATENT OFFICE.

RENÉ ALFRED LAURENT VOLET, OF PARIS, FRANCE.

COMMUTATOR AND THE LIKE.

1,401,016.

Specification of Letters Patent. Patented Dec. 20, 1921.

Application filed October 6, 1920. Serial No. 414,985.

To all whom it may concern:

Be it known that I, RENÉ ALFRED LAURENT VOLET, a citizen of the French Republic, residing at Paris, France, have invented 5 certain new and useful Improvements in Commutators and the like, of which the following is a specification.

This invention refers to devices made up from a ring of units of wedge shape having 10 wires connected thereto, and its most useful application is to the construction of commutators for electrical machines, especially those of small size, although the invention may be applied to other devices.

15 The principal object of the invention is to simplify the construction of devices of the class in question, thus rendering them cheaper to manufacture, while at the same time they are stronger than those constructed up to the present.

The invention relates primarily to devices of the kind having wedge shaped elements provided with means integral therewith for the attachment of the wires to be connected 25 thereto and consists in forming such means of attachment as eyelets suitable for the reception of the said wires.

It further relates to devices of the kind in which the elements are insulated from one 30 another by an insulating material, for instance bakelite, which can be poured between the elements, and the invention refers to a construction wherein the means of attachment for the wires are completely embedded 35 in the insulating material, holes being provided in the insulating material opposite the before mentioned eyelets for the passage of the wires.

The invention, in addition to the constructional features just mentioned which are 40 preferably used in combination also refers to other constructional arrangements which will be more fully described hereafter and to devices embodying such arrangements or 45 constructions.

In order that my invention may be clearly understood, I will now proceed to describe the same with reference to the accompanying drawings which however are merely given 50 by way of example.

Figure 1 shows a part front elevation of a commutator for an electrical machine constructed according to the invention.

Fig. 2 is a side elevation of one of the 55 plates of the said commutator.

Fig. 3 is a plan of the blank from which

the plate is obtained by suitable folding or bending.

Fig. 4 is a rough perspective view of a contoured block by simply cutting, which, 60 blanks such as those shown at Fig. 3 can be obtained.

Fig. 5 shows partly in axial section and partly in elevation a commutator constructed according to another method of carrying 65 out the invention.

Fig. 6 is a part side elevation of the said commutator.

Figs. 7 and 8 show respectively in side and in front elevation one of the plates of 70 the same commutator.

In constructing a commutator according to the invention I proceed substantially as follows:

In making the plates which are of the 75 known type having the "radials", integral with the body of the plate, I provide a contoured block *a*, the shape of which is shown at Fig. 4, the said block being of any suitable material such for instance as electrically 80 pure copper.

This block is formed with a lower flat surface *a*¹, a relatively shallow middle portion *a*² and thickened portions *a*³ toward each edge, these latter portions having their upper surfaces *a*⁴ so inclined outward and downward that the angle α which the upper surface makes with the lower surface *a*¹ is substantially equal to half the angle ϵ which the two outer faces of the finished commutator plate make with one another. 90

The block is also so shaped that it is symmetrical in a plane perpendicular to the lower surface *a*¹ and to the longitudinal axis *a*⁰. 95

The block is cut into a series of blanks, one of which is shown at Fig. 3. Each of these blanks comprises two identical side portions which are equal in length to the length of the finished plate and each furnished with a dove tail. It also has a transverse portion constituting a kind of bridge between the side portions and connecting them toward one extremity. This bridge portion may be made, as shown, of some considerable width. 100

Each of the plates thus formed is folded around the before mentioned longitudinal axis *a*⁰ of the lower surface of the contoured block from which the blank has been made, and by the use of an appropriate mandrel a 110 sort of eye or eyelet is produced at the bend.

A suitable number of these wedge shaped elements are provided for the device.

They are assembled in ring form in the ordinary manner, with insulating material b interposed between them in the usual way.

Into the eye or eyelet provided on each element the wires c to be attached thereto are passed.

For the purpose of securing them in position I compress the side walls of the eyelet by means of a suitable tool, such as a pair of flat nosed pliers, so as to crush the wire c and nip them in position. Or again, I may compress the walls as previously described and in addition rivet the sides of the plate together by means of a rivet d preferably passing through holes provided for that purpose in the portions of the blanks in the neighborhood of the sides of the eyelet as shown; or I may introduce solder or the like and then compress the sides of the walls by means of a heated tool so that in addition to being compressed fusion of the solder or the like takes place to further obtain a perfectly secure connection.

By the construction just described I can obtain an extremely efficient commutator for an electrical machine.

While the foregoing construction produces a highly satisfactory article I prefer in some cases to adopt the following constructions which may be used in combination with those already described or independently thereof.

I provide a mold, of any usual description, into which are inserted the commutator plates formed and arranged substantially as hereinbefore described. This mold is of such size that the plates may be completely or partially embedded in the insulating material such as bakelite, thus forming the device when molded with a circular casing e shown at Figs. 5 and 6, with the walls so shaped as to allow for access of air. In the preferred construction, only the edges of the radials which are located on the side toward the brushes to be used with the armature are visible, and the corresponding edges of the eyes a^o , which latter open into conduits e^o , provided in the extension of the said eyes passing to the side walls e^1 of the device.

The mold is also preferably so formed that it enables a tube f to be furnished concentric to the axis of the casing, which tube is mounted on the axle of the armature of the electrical machine. Provision is also made for struts or bindings for increasing the strength, such as those indicated at g and h on Figs. 5 and 6 and the shape is such that the edges of the casing are adapted to support the extremities of the windings of the armature located at the side of the commutator.

After the molded device has been dried and extracted from the mold, the commuta-

tor is finished by passing one or more wires into each of the eyes a^o , the proper joint or connection being completed if found desirable, by means of a drop of solder at the edge of the eye.

By the foregoing construction I obtain a commutator for electrical machines, the working of which will be understood without further description, and which fulfills practical requirements in an admirable manner.

Owing to the fact that the radial members form an integral part of the plates instead of being simply carried by the latter, and owing to the casing e and the inclosed radials constituting a block all risk is obviated of the radials becoming detached through the centrifugal force. Again, owing to the manner in which the wires are connected to the radials and in which the eyes for the reception of these wires are inclosed in the insulator all risk is obviated of the wires becoming detached either through the effects of centrifugal force or the heating due to working. Moreover, where as in the case of a device shown in Figs. 1 to 4 the transverse portion of the blank from which the plate is formed is of relatively considerable width, so that the radials are of considerable width, these latter during operation produce a ventilating effect which is very strong. This effect may be increased where desired by increasing the radials and so forming them, for instance with hollows that they form true ventilator vanes.

It will be understood as has already been remarked that the invention is not limited to the particular methods of carrying it into effect or to the constructional embodiments which have been more particularly indicated.

It includes various modifications, among which the following may be mentioned:—

In place of making up the plates from blanks as previously described, they may be shaped as shown at Figs. 1 and 2 by other means, for instance by casting.

In other cases the plates while having the same shape as those illustrated at Figs. 1 and 2 may be provided with eyelets formed by turning or rolling over the edge as shown at Figs. 6 and 7.

Or again, each of the plates may be so formed that a small tongue is provided at the end of a radial. This tongue may be turned over a mandrel so as to form an eyelet and the extremity of the tongue may be fixed in any suitable manner, for instance by means of a rivet analogous to the rivet d shown at Figs. 1 and 2.

What I claim and desire to secure by Letters Patent of the United States of America is:—

1. In a commutator or like device, a ring of wedge shaped elements, each of such ele-

- ments having formed integral therewith an eye for the reception of the wires to be connected thereto, insulating material between the said elements, an inclosing casing of insulating material in which the said elements are embedded, the said casing being provided with holes leading to the said eyes for the passage of the wires, substantially as described.
2. In a commutator or like device, a wedge shaped element, formed from a single blank of appropriate metal, provided with an enlarged end portion, and a connecting bridge portion, the blank being so shaped that when it is folded over so that the extremities meet, the middle portion constitutes the radial for the attachment of the wires, substantially as described.
3. In a commutator or like device, a wedge shaped element, formed from a single blank of appropriate metal, provided with an enlarged end portion, and a connecting bridge portion, the blank being so shaped that when it is bent with the middle portion passing around a mandrel and the ends are brought together an eye is formed for the insertion of the wires, substantially as described.
4. In a device of the type described, a ring of wedge shaped elements, each of such elements having formed integral therewith, an eye for the reception of the wires to be connected thereto, the radials of the said elements being moreover so shaped as to constitute the vanes of a fan substantially as described.
5. In a commutator or like device, a ring of wedge shaped elements each of such elements having formed integral therewith an eye for the reception of the wires to be connected thereto, insulating material between the said elements, an inclosing casing of insulating material in which the elements are embedded, the said casing being provided with holes leading to the said eyes in one direction and having the eyes at the edge thereof in the other direction and wires soldered to the said eyes, substantially as described.
6. In a commutator or like device, a ring of wedge shaped elements each of such elements having formed integral therewith an eye for the reception of the wires to be connected thereto, insulating material between the said elements, an inclosing casing of insulating material in which the elements are embedded, the said casing being provided with holes leading to the said eyes in one direction and having the eyes at the edge thereof in the other direction and wires soldered to the said eyes, substantially as described.
7. In a commutator or like device, a ring of wedge shaped elements each of such elements having formed integral therewith an eye for the reception of the wires to be connected thereto, insulating material between the said elements, and a casing of insulating material surrounding one end of said ring of wedge shaped elements and adapted to support the extremity of an armature winding adjacent to the commutator substantially as described.

In testimony whereof I have hereunto set my hand in presence of a subscribing witness.

RENÉ ALFRED LAURENT VOLET.

Witness:

VICTOR MARENDSWSKI.
